United States Patent Office

Des. 199,709
Patented Dec. 1, 1964

199,709

DISPLAY CASE OR SIMILAR ARTICLE

Raymond D. Harrison, Arlington Heights, Ill., assignor to W. A. Sheaffer Pen Company, Fort Madison, Iowa, a corporation of Delaware

Filed Nov. 6, 1963, Ser. No. 77,315

Term of patent 14 years

(Cl. D80—11)

FIG. 1

The writing implements and their holders shown in broken lines in FIG. 1 are included for illustrative purposes only.

I claim:

The ornamental design for a display case or similar article, as shown and described.
